UNITED STATES PATENT OFFICE.

LOUIS M. HARTWICK AND PATRICK J. BROWN, OF CLEVELAND, OHIO; SAID HARTWICK ASSIGNOR OF HIS ENTIRE RIGHT TO THE FRAZIER-SHEAL COMPANY, OF CLEVELAND, OHIO, A CORPORATION OF OHIO.

HOT-BLAST STOVE.

1,416,198.

Specification of Letters Patent. Patented May 16, 1922.

Application filed January 20, 1919. Serial No. 272,003.

To all whom it may concern:

Be it known that we, LOUIS M. HARTWICK and PATRICK J. BROWN, citizens of the United States, residing at Cleveland, in the county of Cuyahoga and State of Ohio, have invented a certain new and useful Improvement in Hot-Blast Stoves, of which the following is a full, clear, and exact description, reference being had to the accompanying drawings.

This invention relates to hot blast stoves and has for its general object to provide a stove of this character with means whereby the checker work may be supported in a particularly efficient manner and one wherein the checker work may be made of bricks (or like refractory heat-imparting blocks) of standard or unit size. By reason of the means employed for supporting the checker work we are enabled to employ for the bottom or foundation course single unit bricks or blocks; also to use for all of the courses above such bottom or foundation course single unit bricks or blocks.

We accomplish these results in and through the construction and arrangement of parts shown in the drawings forming part hereof wherein Fig. 1 represents a central vertical sectional view through a hot blast stove containing our invention; Fig. 2 a sectional view through the stove shown in Fig. 1, the quadrants of Fig. 2 corresponding respectively to the section lines *a—a*, *b—b*, *c—c*, and *d—d* of Fig. 2, being indicated at *a*, *b*, *c* and *d*, respectively; Fig. 3 a sectional view corresponding to the line 3—3 of Fig. 1; Fig. 4 a sectional view corresponding to the line 4—4 of Fig. 1; Fig. 5 a sectional view corresponding to the line 5—5 of Fig. 3, and Fig. 6 is an enlarged detail plan view of the checker work shown in the quadrant *d* of Fig. 2.

Describing by reference characters the various parts illustrated herein, 1 denotes the base of a hot blast stove, the said base being shown as of masonry (such as brick work) and having therein an annular flue 2 and a central transverse flue 3. The base 1 is preferably circular in outline and supports at its peripheral portion and externally of

the flue 2 an annular wall 4, preferably of masonry (such as brick work); also, within the outer wall 4 and also within the flue 2, the base supports an inner annular wall 5, which may be constructed of material similar to that employed in the production of the wall 4. 6 denotes a dome supported by the outer wall 4. This dome is also preferably formed of masonry and is provided with a central opening having a removable closure 8. The outer masonry wall and the dome are enclosed by a sheet metal covering 9, provided at its upper end with an opening 10 having a collar 11 surrounding the same.

Above the base 1 and extending through the walls 4 and 5, is a conduit 12 which may be conveniently formed within a masonry arch 13 supported on said base, the inner end of said passageway communicating with the central vertical chamber 14 enclosed by the wall 5. Opposite the conduit 12 is a conduit 15, which also extends through the walls 4 and 5 and which may also be formed within a masonry arch 16 supported on the base. Beneath the arches 13 and 16, the flue 2 is provided with supporting arches 17 for the conduits thereabove. The flue 3, which is located within the base 1, is provided with an arch 18 at the top thereof. The outer end of the conduit 15 communicates with a vertical conduit 19 from which there extends a conduit 20. In the conduit 19 is located a valve 21 cooperating with a seat 22, the stem 23 of said valve being provided with a chain or other flexible operating device 24 provided with a counterweight 25 and extending over a sprocket 26, the shaft of which is provided with a hand wheel 27.

The annular flue 2 extends upwardly from the base 1 and communicates with and forms a continuation of the annular chamber 28 which contains the checker work. In order to support the checker work, radial arches 29 are provided above the flue 2. These arches may be formed of brick, as indicated, and are each provided with an extension 30, which may be of brick work, the tops of the extensions being in the same plane as the horizontal ledges 31 and 32, located at the base of the chamber 28. These arches and

their extensions, together with the ledges 31 and 32, provide supports for the bars on which the checker work is carried.

Communicating with the lower portion of the flue 2 is an inlet connection 33 extending through the outer portion of the base 1. Opposite this connection is an outlet connection 33^a having a cover 34, by the removal of which the connection 33 may be placed in communication with a chimney (not shown).

35 denotes a bar, one end of which is supported upon the longitudinal central portion of the top or extension 30 of one of the radial arches 29. This bar extends at right angles to the arch extension, the opposite end of the bar resting upon and being supported by the ledge 32 and the intermediate portion of the bar being supported by the top or extension 30 of one of the other arches. The other bars 35^a are supported in like manner. These bars, being of greater length than the bar 35, are shown as supported by two or more arch extensions. A certain number of the bars, 35^b, will be supported at one end by the ledge 31, with which the extensions 30 merge, by one or more of the arch extensions 30, and by the ledge 31. The bars may be of any substantial heat-resistant material, such as steel billets, or concrete beams reenforced by metal. The bars are arranged parallel with each other and equidistantly apart, the arrangement shown being such that two of the bars will rest throughout their lengths upon arch extensions—see 35^c. The bars are so arranged that the distances between their longitudinal centers will be equal to the length of the bottom or supporting course of bricks or blocks. For instance, these 40 bricks or blocks may be 11 $\frac{1}{2}$ "x6"x3". The blocks, indicated at 36, are stood on edge upon the bars 35^a—35^c, with their ends at the longitudinal centers of said beams. The blocks which contact with the walls 4 and 5 will be broken or formed into bats of appropriate shape for this purpose; but the arrangement permits the use of a course of single unit blocks 36 for the foundation course of the checker work. This arrangement is shown in quadrant c on Fig. 2 of the drawing.

For the next course and the succeeding courses, blocks or bricks of smaller size are employed. For instance, with blocks of the 55 dimensions given for the bottom or foundation course, the blocks in the checker work thereabove may be 9"x4 $\frac{1}{2}$ "x2 $\frac{1}{2}$ ", the blocks 36 being laid in rows the longitudinal centers whereof are 5 $\frac{1}{2}$ " apart or half the length of 60 such blocks. The bars 35, 35^a and 35^b are preferably square in section and, with the arrangement shown herein may be 4" square.

With this arrangement, the checker-work 65 blocks 37 may be laid at right angles to the

blocks 36 and are of such length as to be supported at their central portions by one of the blocks 36, with their ends overlapping about $\frac{1}{4}$ " on the blocks 36 located on each side of such central block. This will leave 70 between the ends of adjacent blocks 37 a space on the blocks 36, which supports such ends, sufficient for a similar block 37^a, arranged at right angles to the first mentioned blocks and extending longitudinally of the 75 block 36. As each block 36 has a length equal to the combined length and thickness of a block 37, 37^a, it can support two of the last mentioned blocks, one extending longitudinally thereof and the other arranged at 80 right angles thereto.

The blocks in courses above that shown in quadrant d of Fig. 2 will be of the same size as the blocks in such quadrant, and may be superposed directly upon the blocks of the 85 courses therebeneath, respectively. This arrangement enables us to employ, as pointed out hereinbefore, a single unit size block for the foundation course and a single unit size block for the remaining or checker work 90 courses thereabove, and these blocks may be conveniently made as bricks.

In operation gas for preheating purposes will be admitted through conduit 12 to the central combustion chamber 14 and there ignited. The burning gases and products of combustion will ascend the chamber 14 beneath the dome 6 and will then pass downwardly through the checker work in chamber 28, heating the same, the gases being collected in the flue 2 and being discharged through the connection 33^a, the cover 34 having been removed for this purpose and the connection having been placed in communication with the chimney. After the preheating operation, cold air will be admitted through the connection 33 to the flue 2, will ascend through the checker work in the chamber 28 and pass downwardly through the central chamber 14 and outwardly 100 through the conduits 15, 19 and 20, the valve 21 being opened for this purpose.

Suitable clean out openings 38 are provided for the flue 2, said openings being provided with covers 39. The conduit 15 115 will be provided with a similar cover 40 and the gas supply conduit 12 with a cover or valve 41.

The blocks 36 of the lower or supporting course and the blocks 37, 37^a of each course 120 thereabove will be of refractory material, preferably brick. While we have given the dimensions of blocks herein, it will be understood that these dimensions are for purposes of illustration. For instance, the 125 blocks 36 may be made of greater thickness than specified herein, should it be found desirable to provide a wider margin on each side of the blocks 37^a for the support of the ends of the blocks 37. Furthermore, it is not 130

necessary that the blocks of each checker work course coincide in position with the supporting blocks of the course therebeneath.

Having thus described our invention, what we claim is:—

1. In a hot blast stove, the combination of an inner wall enclosing a central chamber and an outer wall forming with the inner wall an annular chamber surrounding the central chamber, arches extending radially between the inner and the outer wall, each arch having a flat top, transverse parallel bars supported on said arches, and checker work supported by said bars. 70
- 10 2. In a hot blast stove, the combination of an inner wall enclosing a central chamber and an outer wall surrounding the inner wall and forming therewith an annular chamber, annular ledges projecting respectively outwardly from the inner wall and inwardly from the outer wall near the bottom of said chamber, arches extending radially from the inner wall to the outer wall beneath said ledges, transverse parallel bars supported by said arches and said ledges, and checker work supported by said bars. 80
- 15 3. In a hot blast stove, the combination of an inner wall enclosing a central chamber and an outer wall surrounding the inner wall and forming therewith an annular chamber, annular ledges projecting respectively outwardly from the inner wall and inwardly from the outer wall near the bottom of said chamber, arches extending radially from the inner wall to the outer wall beneath said ledges, said arches having flat tops in the plane of said ledges, transverse parallel bars supported by the tops of said arches and said ledges, and checker work supported by said bars. 90
- 20 4. In a hot blast stove, the combination of an inner wall providing a central chamber, an outer wall surrounding the inner wall and forming therewith an annular chamber, equidistantly spaced parallel bars in the lower portion of said annular chamber, means for supporting said bars, parallel blocks having their ends supported on the longitudinal centers of adjacent bars, and a course of blocks supported on the first mentioned blocks, said course comprising blocks of a smaller size than the first mentioned blocks, some of the blocks of the second course being mounted upon and extending longitudinally of the first mentioned blocks and other blocks of such second course being arranged at right angles to the first mentioned blocks and having their ends supported on the marginal portions thereof, and their central portions supported each by one of the first mentioned blocks. 105
- 25 5. In a hot blast stove the combination of an inner wall providing a central chamber, an outer wall surrounding the inner wall and forming therewith a chamber, bars interposed between the inner and outer walls of said chamber, said bars being arranged parallel and equidistantly spaced, a course of parallel blocks each of which extends between and is supported by adjacent bars, and a course of blocks supported by the first mentioned blocks, the length of each block of the first course being at least equal to the combined length and thickness of one of the blocks of the second course and each being of greater thickness than the blocks of the second course whereby certain blocks of the second course may extend lengthwise of the blocks of the first course leaving marginal edges on such blocks of the first course adapted to support the ends of other blocks of the second course which extend at right angles to the blocks thus supported on the central portions of the blocks of the first course. 110
- 30 6. In a hot blast stove, the combination of an inner wall providing a central chamber therewithin, an outer wall surrounding the inner wall and forming therewith an annular chamber, bars interposed between the inner and outer walls near the bottom of the said annular chamber, said bars being arranged parallel and equidistantly spaced, a course of parallel blocks each of which extends between and is supported by adjacent bars, and a course of blocks supported by the first mentioned blocks, the length of each block of the first course being at least equal to the combined length and thickness of one of the blocks of the second course, the distance between longitudinal centers of the first mentioned blocks being equal to half the length of such blocks and each such block being of greater thickness than the blocks of the second course, whereby certain blocks of the second course may extend lengthwise of the blocks of the first course leaving marginal edges on such blocks of the first course adapted to support the ends of other blocks of the second course which extend at right angles to the 120
- 35 7. In a hot blast stove, the combination of an inner wall providing a central chamber, an outer wall surrounding the inner wall and forming therewith an annular chamber, bars interposed between the inner and outer walls near the bottom of the said annular chamber, said bars being arranged parallel and equidistantly spaced, a course of parallel blocks each of which extends between and is supported by adjacent bars, and a course of blocks supported by the first mentioned blocks, the length of each block of the first course being at least equal to the combined length and thickness of one of the blocks of the second course, the distance between longitudinal centers of the first mentioned blocks being equal to half the length of such blocks and each such block being of greater thickness than the blocks of the second course, whereby certain blocks of the second course may extend lengthwise of the blocks of the first course leaving marginal edges on such blocks of the first course adapted to support the ends of other blocks of the second course which extend at right angles to the 130

blocks thus supported and each of which is supported at its central position by an intermediate block of the first course.

8. In a hot blast stove, the combination of an inner annular wall providing a central chamber, an outer wall surrounding the inner wall and forming a chamber therewith, each of said walls being provided with a

ledge projecting toward the other, bars supported by said ledges, and checker work supported by said bars. 10

In testimony whereof, we hereunto affix our signatures.

LOUIS M. HARTWICK.
PATRICK J. BROWN.
